UNITED STATES PATENT OFFICE.

JAMES AMASA BIGELOW, OF MELBOURNE, VICTORIA, ASSIGNOR TO JOHN HYAM NATHAN, OF SYDNEY, NEW SOUTH WALES.

CONSTRUCTION OF BEER-ENGINES.

SPECIFICATION forming part of Letters Patent No. 401,406, dated April 16, 1889.

Application filed July 16, 1887. Serial No. 244,543. (No model.) Patented in Victoria June 20, 1884, No. 3,748, and April 29, 1887, No. 5,043; in New Zealand November 21, 1884, No. 1,303; in South Australia April 29, 1887, No. 800; in England May 31, 1887, No. 7,904; in New South Wales July 20, 1887, No. 2,132, and in Queensland August 26, 1887, No. 268.

To all whom it may concern:

Be it known that I, JAMES AMASA BIGELOW, mechanical engineer, a subject of the Queen of Great Britain, formerly residing at No. 203 5 George Street, West Sydney, in the Colony of New South Wales, Australia, but now residing in Melbourne, in the Colony of Victoria, Australia, have invented certain new and useful Improvements in Beer-Engines, (for which 10 in part I have received Letters Patent in the following countries: Colony of Victoria, Australia, June 20, 1884, No. 3,748; Colony of New Zealand, Australia, November 21, 1884, No. 1,303; Colony of Victoria, Australia, April 29, 15 1887, No. 5,043; Colony of South Australia, April 29, 1887, No. 800; Colony of New South Wales, Australia, July 20, 1887, No. 2,132; Colony of Queensland, Australia, August 26, 1887, No. 268, and United Kingdom of Great 20 Britain, May 31, 1887, No. 7,904,) of which the following is a specification.

My invention relates to apparatus for drawing beer or other liquids from a receptacle in a cellar or adjacent store-room and delivering 25 the same to other receptacles upon a bar-counter; and its objects are to provide a simple and efficient apparatus of this character in which the beer or liquids may be cooled or warmed, as desired, and in which also several 30 kinds of beer may be mixed before delivery, and which apparatus may be readily put in order by an unskilled person should any of its parts become disarranged during its operation.

35 The invention consists in the construction and arrangement of parts of the beer-engine, hereinafter particularly described, and pointed out in the claim.

Reference is to be had to the accompanying 40 drawings, forming a part of this specification, in which similar letters of reference indicate corresponding parts in all the figures.

Figure 1 is a central vertical sectional elevation of the pump-barrel and cooling and 45 warming chamber of the apparatus, other parts also being shown broken away and in section. Fig. 2 is a plan view of the bottom plate

of the same, parts being shown in section and other parts indicated by broken lines. Fig. 3 is a similar view of the top plate of the 50 same, parts being shown in section and in full and broken lines. Fig. 4 is a central vertical sectional elevation of one of the suction-pipes of the apparatus and the self-acting check-valve therein, and a plan view of the union 55 attached to said pipes. Fig. 5 is a view in side elevation of the apparatus, parts being shown broken away and in section. Fig. 6 is a view in front elevation of the same, parts being shown broken away. 60

The beer-engine comprises a circular metal plate, P', adapted to rest upon the bar-counter B', and provided with a circular groove, G', in which packing material is inserted, said plate being provided with a central opening 65 for the passage of the plunger-rod P², and suitable apertures to receive an inlet-pipe, I, an outlet-pipe, O', and suction-pipes S, and to permit communication between a spray-pipe, s p, on said plate, and a chamber, I', beneath 70 said plate. Upon said plate and the packing in said groove rests a pump-barrel, B, and concentric therewith a cylinder, C', whereby a chamber, C, is formed between the cylinder and said barrel. Upon the upper ends of the 75 barrel and cylinder rests a circular metal plate, P, provided with a groove, G, in which packing material is fitted. Said plate is provided with a central opening, in which plays vertically a self-acting outlet-valve, V², and 80 an outlet-pipe, O, leads therefrom to a connection with a delivery-pipe, S W, provided at its outer end with a tap, T'. To said plate is hinged a cap or cover, c, and in said plate are provided hand-holes H H, closed by cov- 85 ers hermetically sealed by screw-nuts.

The plates P and P' are held together by adjusting-rod R, provided with adjusting rings and screws A and jam-nuts at their extremities. The suction-pipes S are each provided with a regulating-tap, T, a self-acting check-valve, V, and a pressure-gage, p g. 90

In the chamber C, surrounding the barrel B, is a perforated spray-pipe, s p, commun-

eating with a chamber, I', beneath the plate P', into which the inlet-pipe I leads from a water-supply.

In the barrel B is the hollow plunger *p l*, 5 provided with suitable openings for the passage of liquid to the barrel from the pipes S, said plunger being fitted with a ring of packing material between it and the sides of the barrel, and provided with a self-acting outlet-valve, V'.

The plunger-rod P² is provided beneath the counter with a cross-head, *c h*, and connecting-rods *c r* are attached thereto and to one end of a treadle, *t*, which is fulcrumed at F 15 to the floor beneath the counter, and which treadle is connected by an elastic band or spring, *s a*, to a shelf, B², beneath said counter. The pump-barrel B serves also as a mixing-chamber for several different kinds of beer 20 or liquor delivered to it by the suction-pipes S from the casks or barrels in the cellar or storage-room. I construct both said barrel B and the cylinder C of glass, the same being a non-corrosive material and preferable for the pur- 25 poses of construction and cheapness, and also serving for ornament, although except in the latter respect any other suitable non-corrosive material may be employed in their construction.

The plate P is covered by an ornamental cap, *c*, constructed either of metal or of glass, which conceals the top mechanism of the beer-engine, and said cap hinges back at H' to admit of access generally to the outlet-valve V² in the upper part of the apparatus, 35 and also to admit of the removal of the plate P for free access to the barrel B and chamber C, if at any time required. The outlet-valve V² in the plate P regulates the discharge of liquor from the pump-barrel B to and through 40 the outlet-pipe O, which crosses the top of the plate P, with which pipe the draw-off tap T' is connected by the swan's-neck pipe *s w*, the tap being thus brought level with or below the bar-counter B'.

The hand-holes H H in the plate P, which lead into the chamber C, are to admit of the introduction of a heating or cooling medium within said chamber, and said holes are closed 50 by covers which are hermetically sealed by suitable screw-nuts.

The bottom plate, P', is provided with a central opening leading to a chamber, S², beneath said plate, from which leads a pipe, S', integral therewith, for connection to the suction-pipes attached to the receptacles containing the beer. Said plate is also provided with an opening leading to a chamber, I', to which is connected an inlet-pipe, I, for the introduction 55 of hot or cold water to the chamber C, and with a proper opening for the passage of the plunger-rod P².

The circular perforated spray-pipe *s p* is fixed upon the plate P' in the center of the 60 chamber C and communicates with the chamber I', so that water entering the pipe I will pass therefrom through the chamber I' to the

pipe *s p*, and exit therefrom in the form of spray. An outlet-pipe, O', entering said chamber through a proper opening in the plate 70 P', carries away the waste water from said chamber.

The plunger *p l* is arranged to work vertically, and it being a matter of difficulty to obtain a cylinder of glass which will be quite 75 true and free from inequalities I construct said plunger, so that it will adjust itself to the inequalities of the barrel, in the following manner: I so construct its cup *p c* as to admit of its receiving a ring of suitable material for 80 packing, and for the purpose I have found green hide to serve best, and such packing is screwed into position and held in place on said cup by a metal ring, so as to leave a space of, say, one-fourth of an inch between the packing material and the sides of the plunger, whereby, during the upward stroke of the plunger, the pressure of the liquor causes the packing material to expand and press against the sides of and fit the inequalities of the 85 pump-barrel.

The plunger-rod P² passes down from its attachment to the plunger to a cross-head, *c h*, beneath the counter B', which cross-head is attached to the connecting-rods *c r*, attached 95 to the treadle *t*, which is fulcrumed at F to the floor beneath said counter. Said treadle is kept normally in a horizontal position by an elastic band or spring, *s a*, attached at either end to said treadle and to a shelf, B², 100 beneath said counter. Said treadle may be fulcrumed upon a support seated in the floor or ground of the cellar, and the spring attachment may be attached to the ceiling over the cellar as desired. 105

Two suction-pipes, S, are shown in the drawings; but as many of such pipes as there are different kinds of liquors which are to be mixed together in the pump-barrel may be fitted to the plate P', proper openings therein having been made for that purpose, and each pipe be provided beneath the counter B' with a tap, T, and connected by suitable unions or couplings with supply pipes or connections leading from the casks in the cellar or other 110 place of storage. 115

I construct the suction supply, inlet and outlet pipes, plates, plunger, plunger-rod, and the other connections with the barrel and chamber of electroplated metal, having found the same to be the best for use, as being non-corrosive, and also ornamental in connection with the glass barrel and cylinder; but, except in the latter respect, the use thereof is not an absolute requirement in connection 120 with my invention. 125

The plates P and P' may also be constructed of glass, with slight variations in their adjustments adapted thereto.

The treadle *t* is so adjusted that one stroke 130 of the plunger and its rod caused by operating the treadle toward the floor will pump up a certain fixed quantity of liquor, and that quantity may be registered by means of the

pressure-gages p g , which may be such as are usually employed for measuring liquids, and located in each suction-pipe S below the check-valve V therein, and by properly regulating 5 the taps in the suction-pipes the liquor forced up by the action of the treadle may be mixed in the proportions desired in the barrel B .

I have found that by adjusting the treadle t so as to give it play within a space of four 10 and a half inches from the floor, and using one-inch supply-pipes from the casks, by operating said treadle one pint of liquor is delivered to said pump-barrel at each stroke of the plunger-rod.

15 The chamber C may be filled with ice or hot or cold water through the hand-holes H H in the plate P , or with cold or hot water sprayed into it through the pipe I and spray-pipe s p , as desired, the waste water passing 20 off, as before stated, through the pipe O' .

Having thus described my invention, what I claim as new, and desire to secure by Letters Patent, is—

25 In a beer-engine, the combination of the following elements: a base-plate, a pump-barrel on said plate, a valved plunger and its rod

working upwardly in the pump-barrel and base-plate, a cylinder surrounding the pump-barrel and forming a chamber therebetween, a circular spray-pipe in said chamber, an inlet-pipe communicating with the spray-pipe, an outlet-pipe leading from the base of the chamber, a cap-plate centrally apertured over the pump-barrel and fitted therewith a valve, and having openings over said chamber provided with detachable covers, adjustable connections between the base and cap plates, an outlet-pipe leading from the valved aperture in the cap-plate and provided with a delivery-tap, valved pipes connecting the pump-barrel with liquor-receptacles, and a foot-lever for operating the plunger-rod, all constructed, arranged, and adapted to operate as herein shown and described.

JAMES AMASA BIGELOW.
